DESIGN FOR A DISTILLATION TESTING APPARATUS

Alexander I. Newman, Chicago, Ill., assignor to Precision Scientific Company, Chicago, Ill., a corporation of Illinois

Application March 14, 1940, Serial No. 90,917

Term of patent 14 years

To all whom it may concern:

Be it known that I, Alexander I. Newman, a citizen of the United States, residing at Chicago, in the county of Cook and State of Illinois, have invented a new, original, and ornamental Design for a Distillation Testing Apparatus, of which the following is a specification, reference being had to the accompanying drawing, forming part thereof.

Figure 1 is a front perspective view of a dis-

tillation testing apparatus embodying my new design.

Fig. 2 is a left end elevational view of the same on a slightly smaller scale.

Fig. 3 is a rear elevational view of the same.

I claim:

The ornamental design for a distillation testing apparatus, substantially as shown.

ALEXANDER I. NEWMAN.
